UNITED STATES PATENT OFFICE.

CHARLES E. DURYEA, OF ST. LOUIS, MISSOURI.

BICYCLE.

SPECIFICATION forming part of Letters Patent No. 364,231, dated June 7, 1887.

Application filed September 28, 1885. Serial No. 178,484. (No model.)

To all whom it may concern:

Be it known that I, CHARLES E. DURYEA, of St. Louis, Missouri, have made a new and useful Improvement in Bicycles, of which the following is a full, clear, and exact description.

The improvement relates partly to the handle-bars, partly to the pedals, and partly to the head, of the bicycle.

In the annexed drawings, making part of this specification, Figure 1 is a side elevation of the improved bicycle, and Fig. 2 is a front elevation. Figs. 3 to 10 are details upon an enlarged scale, Fig. 3 being a sectional view of a pedal, the section being on the line 5 5 of Fig. 4; Fig. 4, a plan of a pedal; Fig. 5, an outer end elevation of a pedal; Fig. 6, a sectional elevation of the head; Fig. 7, a plan, partly broken away, of the head, and Fig. 8 a side elevation showing the mode of attaching a handle-bar to a fork already made. Fig. 9 is a detail showing the handle extensible. Fig. 10 is a detail showing the handle extending backward, outward, and upward.

The same letters of reference denote the same parts.

A, Figs. 1 and 2, represents a bicycle of the customary construction, saving as modified by the present improvement. B B' represent the handle-bars. They are attached adjustably or otherwise to the fork C, and respectively on opposite sides thereof, extending from a point about midway between the hub D and the head E, backward to about opposite the rear end of the saddle F, substantially as is represented at b in Fig. 1; thence laterally outward from the wheel sufficiently for the rider's leg to pass between the wheel G and the upright portion of the handle-bar, substantially as is represented at b', Fig. 2, and thence upward, as is represented at b'', Figs. 1 and 2, and at the upper end being provided with the handle b'', which preferably points horizontally forward, as shown in Fig. 1. The handle-bars thus constructed may be made in one piece with the fork, as in Fig. 1, or they may be attached at any desired point to a fork, as in Fig. 8.

The handle-bar B can be so made as to be readily attached to almost any fork, and as is now generally indicated in Fig. 8, where the end of the bar B is branched and secured to the fork by a screw through its ends at any de-

sired location; but in the merely mechanical details of carrying out this idea many different methods of construction may be employed. The upright part (see Fig. 9, not 55 shown in Figs. 1 and 2) may be made vertically adjustable or extensible, to enable the handle b'' to be suited to the rider, who, when in the saddle, grasps the handles at each side of him and guides the bicycle as if the handles 60 were attached to an ordinary handle-bar.

The advantage of this form of handle-bars is that it enables the rider to mount from in rear of the large wheel in the usual manner, and to dismount either in the rear or in the 65 front of the large wheel. It also permits of an upward pull upon the handle in propelling the wheel.

The construction of the pedal H, as shown in Figs. 3, 4, and 5: The pedal-pin h is attached to the crank h' by means of the nut h''. The inner end of the pedal-pin at h'' is threaded. The outer end, h', is pointed. The pedal-frame h'' is held in place and adapted to rotate on the pedal-pin by means of the nuts h⁶ and h⁷, the 70 balls h⁸ and h⁹. The pedal-frame at h¹⁰ is inclosed, both to exclude dust and to retain the oil upon the bearing and prevent it from being rubbed against. The nuts h⁶ and h⁷ are beveled at their opposing ends, and after they are 75 screwed on the threaded end of the pedal-pin into place their beveled ends jointly provide a bearing for the balls h⁸. The inner side of the pedal-frame bears upon the balls h⁸. The outer side, at h¹⁰, bears upon the balls h⁹, and 80 by adjusting the nuts h⁶ and h⁷ upon the pedal-pin, the balls h⁸ and the pedal-frame are drawn 85 sidewise upon the pedal-pin, so as to hold the part h¹⁰ of the pedal-frame and the balls h⁹ against the pointed end h', and the pedal is 90 thereby held properly in place. All the parts of the pedal can be separated by removing the nut h'' from the pedal-pin, detaching the pedal-pin from its crank, and then removing the nuts from the pedal-pin.

The backbone I, Figs. 6 and 7, is attached to the fork C by means of the nut K. This nut is beveled at k. The fork is beveled at c, and the backbone at its point of connection with the fork is shaped to form the concave 100 ring i. A series of balls, L, are inclosed between the ring i and the bevels k and c, and

the backbone can be tightened as desired upon the fork by screwing the nut upon the fork projection c' , Figs. 6 and 7.

The structure of the spokes, hub, and rim 5 will not be claimed in this case, as they will form the subject of another application by me for patent thereon. I am aware that heretofore the handle-bar 15 has been angled, but know of no case where it extends backwardly, outwardly, and upwardly.

I claim--

1. In a bicycle substantially as shown, a handle-bar attached at one end to the fork about midway between the hub and head of the fork, and thence extending backward, outward, and upward, substantially as and for the purposes set forth.

2. The combination of the pedal-pin h , the crank h^2 , the frame h^5 , the nuts h^6 and h^7 , and the balls h^8 and h^9 , said pin being threaded and pointed, and said frame being closed at h^{10} , as described.

3. In combination with the fork of a bicycle, a handle-bar vertically adjustable on the fork 25 and having a vertically-adjustable handle and extending from the fork backward, outward, and upward, substantially as and for the purposes set forth.

Witness my hand.

CHARLES E. DURYEA.
